UNITED STATES PATENT OFFICE.

THOMAS V. MADIGAN, OF RED HOOK, NEW YORK.

COVER FOR GARBAGE CANS.

1,409,387.

Specification of Letters Patent. Patented Mar. 14, 1922.

Application filed September 2, 1920. Serial No. 407,662.

To all whom it may concern:

Be it known that I, THOMAS V. MADIGAN, a citizen of the United States, residing at Red Hook, in the county of Dutchess and 5 State of New York, have invented certain new and useful Improvements in Covers for Garbage Cans; and I do declare the following to be a full, clear, and exact description of the invention, such as will enable others 10 skilled in the art to which it appertains to make and use the same.

This invention relates broadly to improvements in garbage cans and has more particular reference to a novel cover for the same.

15 The principal object of the invention is to provide a cover which is equipped with a chamber for containing a disinfectant liquid and a combined handle and valve actuating device which permits the user to admit a 20 small quantity of the disinfectant liquid into the can every time the cover is removed.

Another object of the invention is to generally improve upon devices of this class by producing one of extreme simplicity and 25 durability which is not only novel, and efficient in operation, but is very inexpensive to manufacture and is so designed that it is very easily operated.

Other objects and advantages of the invention will be apparent during the course 30 of the following description.

In the accompanying drawings forming a part of this specification, in which like numerals are employed to designate like parts 35 throughout the same:

Figure 1 is a vertical longitudinal sectional view, with parts in elevation, of a cover constructed in accordance with my invention.

40 Figure 2 is a detail vertical section taken on the plane of the line 2—2 of Fig. 1, looking in the direction of the arrow.

Figure 3 is a detail view of the valve mechanism showing the position that the 45 parts assume when the valve is moved to open position.

Referring to the drawings wherein the preferred embodiment of my invention is clearly disclosed, it will be seen that the 50 numeral 1 designates a garbage can, which may be of any suitable construction. My improved cover for this can is designated, as a whole, by the numeral 2. This cover may be very similar in shape and design to covers now on the market but when constructed in accordance with my invention,

it will include a horizontal partition 3 on its inner face which provides a chamber between itself and the cover, this chamber being adapted to contain a quantity of disinfecting liquid or water as the case may be. 60 In order to supply the chamber with the disinfecting liquid, an inlet, closed by a suitable removable screw-plug or cap 4, is provided. Furthermore, in order to permit the liquid 65 to escape from the chamber into the garbage can, a suitable outlet is provided. This outlet may be formed in various ways, but it is preferably formed by installing a vertical tube 5 in the chamber and providing this 70 tube in one side with a port which communicates with the interior of the chamber. This tube 5 also serves as a guide for the valve 7 and its inner end is extended beyond the partition 3 and reduced in diameter to provide a valve seat 8. With this arrangement, 75 it is to be noted that this valve simultaneously closes the port 6 and the open inner end of the guide tube 5.

The valve is operated from the exterior of 80 the cover by novel means, a part of which also serves as a handle for the cover. This means includes a vertical valve actuating rod 9 which has pivotal connection with the upper end of the valve 7 and also has pivotal 85 connection at its opposite end with the short arm of an L-shaped actuating member 10. Member 10 is pivotally mounted on a stationary bracket 11 which is apertured to permit passage of the curved laterally extending part 12 of the member 10 therethrough. Part 12 serves as a guide for the member 10, increases the rigidity of the structure, and serves to permit the coiled 90 spring 13 to surround it and be interposed 95 between the bracket 11 and the member 10.

In use, the chamber is filled with a disinfecting liquid or water whichever may be desired by removing the cap 4. The cover is then placed on the can and serves to close it 100 in the ordinary manner. Now, when garbage or the like is placed in the can and the cover removed by gripping the members 10 and 11, the pressure exerted against the member 10 will force it towards the member 105 11 and will move the valve 7 to a position to admit liquid into the interior of the can 1. As soon as the cover is in place and the member 10 released, the spring 13 will automatically move the valve 7 to a position to 110 simultaneously close the port 6 and the open inner end of the guide tube 5. With the

construction and arrangement disclosed, it will be seen that the valve may be opened whenever desired, whether the cover is removed or not.

5 From the foregoing description, it will be seen that I have devised an extremely simple and advantageous cover for garbage cans and the like which permits the contents of the can to be disinfected and eliminates bad 10 odors. The construction is extremely simple and inexpensive, and strong and durable. Furthermore, the part of the means for operating the valve serves as a handle for the cover and in this way increases the 15 efficiency of the device. There are no parts to become disarranged or get out of order, thus my device is a decided improvement over the prior art devices with which I am familiar.

20 A careful consideration of the foregoing description taken in connection with the accompanying drawings, will enable persons skilled in the art to which the invention relates to obtain a thorough understanding.

25 For this reason, a more lengthy description is deemed unnecessary.

Effective and advantageous results can, no doubt, be obtained with the construction and arrangement disclosed, and for this reason, 30 this construction and arrangement is taken as the preferred embodiment of my invention. However, I wish it to be understood that various minor changes in the shape, size, and arrangement of parts may be 35 sorted to without departing from the spirit of the invention or the scope of the subjoined claims.

I claim:

1. In a device of the class described, a 40 cover including a liquid container, a vertical tubular valve guide arranged in said container open at its inner end and provided with an inlet port at its side and having a valve seat at its open inner end, a valve slideable in said guide for simultaneously closing said port and the inner open end of said guide, and a handle for said cover including a movable element connected with said valve for moving the valve to an open position 45 when the handle is grasped to lift the cover.

2. A cover for garbage cans provided on its inner face with a horizontal partition

forming a liquid containing chamber, a tubular vertical guide arranged in the latter, said guide being provided adjacent its 55 inner end with an inlet port in communication with said chamber and having its inner end reduced in diameter to provide a valve seat, a valve slideable in said guide for simultaneously closing said port and the inner 60 open end of said guide, an operating rod connected to the valve and extending in through the top of said chamber, and a handle element for said cover including a stationary member and a pivoted member movable towards and away from said stationary member and connected with said operating rod whereby said valve may be moved to an open position when the handle members are 65 grasped and the movable member moved towards the stationary member in lifting said cover.

3. A cover of the type described including a liquid containing chamber provided with an inlet and an outlet; a valve for closing the latter, a valve guide, an operating rod, an exteriorly arranged stationary apertured bracket, an L-shaped operating member pivotally mounted on said bracket and having connection at one of its ends with said 75 valve operating rod, said L-shaped member being provided with a laterally directed curved guide extension passing through the aperture in said bracket, and a coiled spring surrounding the curved guide between the 80 bracket and L-shaped member for returning the valve to effective position.

4. In a device of the class described, a 85 cover including a liquid container having an outlet, a valve for the outlet normally closed, and a handle for said cover, including a stationary element carried by the cover and a movable element having movement transversely of the stationary element toward and away from the same and having 90 connection with said valve for moving the valve to an open position when the handle is grasped to lift the cover and the movable element moved toward the stationary element.

100 In testimony whereof I have hereunto set my hand.

THOMAS V. MADIGAN.
